UNITED STATES PATENT OFFICE

LESLIE O. PARKER, OF ANDERSON, INDIANA, ASSIGNOR TO DELCO-REMY CORPORATION,
OF DAYTON, OHIO, A CORPORATION OF DELAWARE

SIGNAL LAMP

Application filed June 13, 1927. Serial No. 198,403.

This invention relates to combination stop and rear end signal lamps for automotive vehicles, and more particularly to the type of lamp having two light chambers illuminated by one incandescent bulb having two spaced filaments differing in candle power and disposed respectively in the light chambers. The light chambers are closed by panes or lenses providing when illuminated, the stop and rear end signals, respectively.

One of the objects of the present invention is to provide a lamp of this type which is durable and rugged and which may be produced at low cost.

Further objects and advantages of the present invention will be apparent from the following description, reference being had to the accompanying drawings wherein a preferred embodiment of one form of the present invention is clearly shown.

In the drawings:

Fig. 1 is a front view of a lamp embodying the present invention.

Fig. 2 is a sectional view on the line 2—2 of Fig. 1.

Fig. 3 is a view with the lamp door removed looking in the direction of the arrow 3 in Fig. 2.

Fig. 4 is a fragmentary view showing the clinch washer which secures the mounting studs or screws to the switch case.

Fig. 5 is a view of the lamp socket and connector shell 22 viewed in the direction of the arrow 5 in Fig. 2.

The lamp housing 20 has its back wall apertured to receive a connector member comprising sheet metal half shell members 22a and 22b attached as shown in Figs. 2 and 5 by a rivet 22c. The connector 22 is attached to the flange 23 of the housing 20 which surrounds the aperture in the housing back wall. The flange 23 cooperates with the rivet 22c to maintain the members 22a and 22b assembled. The connector 22 provides a socket 24 for receiving two terminal type electrical connection plugs (not shown) adapted to engage contacts 25 and 26 integral respectively with leaf spring conductors 27 and 28 which are insulatingly supported by a body of insulating material 29 within the con-

nector 22. The electrical plug connector is retained in the socket 24 by the usual bayonet slot and pin connections, the bayonet slots in the half shell members 22a and 22b being shown at 30.

Within the housing 20 the connector shell 22 provides a lamp socket 31 for receiving the base 32 of a lamp bulb 33 which encloses filaments 34 and 35 located respectively within light chambers 36 and 39 which are separated by the partition plate 40. The lamp base 32 is retained within the socket 31 by pins 32a extending from it and received by bayonet slots 31a in the shell members 22a and 22b, the lamp terminals 37 and 38 being engaged respectively by the spring contacts 27 and 28.

The partition 40 is provided with an opening 41 through which the lamp bulb 33 extends, and is provided with an ear 42 having a square hole 43 in alignment with a square hole in the back of the housing 20 for receiving the square portion 44 of a bolt 45 which is retained by clinching tangs 46 provided by the housing back wall against the shank of the bolt as shown in Figs. 2 and 4. In like manner a bolt 47 is secured to the lamp housing 20. The bolts 45 and 47 provide means for attaching the lamp housing to a bracket.

Adjacent the front edge of the housing 20 the partition 40 is provided with ears 50 having tapped holes 51 each for receiving a screw 52 which secures the lamp door frame 53 to the housing 20. The frame 53 is provided with apertures 54 and 55 for exposing the lenses or panes 56 and 57 which cover respectively the light chambers 36 and 39. When the screws 52 are tightened, the flange 58 of the lamp door frame 53, which serves as a bezel ring, clamps the edges of the panes 56 and 57 and a sealing gasket 61 preferably of cork against the inwardly turned flange 60 of the lamp housing 20. Thus the lamp door is secured to the housing by the partition 40, and the partition is supported at its front edge by the door frame.

The lamp panes 56 and 57 are made of any suitable transparent material such as pyralin stained or otherwise colored with transparent pigment to the desired color of red.

The letters of the word "Stop" show by transmitted light either a deeper or a lighter shade of red than the background provided by the main portion of the pane 56. The 5 filaments 34 and 35 have a common ground connection to the storage battery or the current source of the lighting system of the automobile through the lamp base 32, lamp socket 31, and housing 20 which is connected 10 with the automobile frame, and the filaments 34 and 35 are connected respectively with the terminals 37 and 38. A brake pedal operated switch is used to complete a circuit from the terminal contact 25 to a current source in 15 order that the filament 34 will burn to illuminate the stop signal when the brakes are applied. The filament 35 is connected with a current source by a switch at the instrument board completing a circuit with the current 20 source and the contact 26 in order that the rear end or tail signal will be visible by the illumination of the pane 57. Preferably the filament 35 is of lower candle power since it is operated continuously when driving or 25 parking at night, and the filament 34 is of higher candle power for rendering the stop lamp plainly visible even when operated in the day time.

The filament 35 is used also to illuminate 30 the rear license plate of the automobile by shining through a pane 70 enclosing an aperture 71 in the bottom of the lamp housing 20. A cork gasket 72 is located between the pane 70 and the bottom wall of the housing and is 35 secured in position by clamp brackets 73 held by screws 74.

While the form of embodiment of the present invention as herein disclosed, constitutes a preferred form, it is to be understood that 40 other forms might be adopted, all coming within the scope of the claim which follows.

What is claimed is as follows:

A lamp socket comprising a pair of similar semi-tubular members secured together 45 to form angularly related bores, one of said bores being adapted to receive a lamp having a plurality of contacts on the base thereof, an insulating plug secured in the other member and provided with a plurality of spring 50 contact fingers arranged in superposed relation and having their ends axially spaced for engagement with the contacts.

In testimony whereof I hereto affix my signature.
